(57) **CLAIM**

The ornamental design for a bottle, as shown and described.

DESCRIPTION

FIG. 1 is a first perspective view of a first embodiment of a bottle;

FIG. 2 is a second perspective view of a first embodiment of a bottle;

FIG. 3 is a front view of the first perspective view;

FIG. 4 is a back view of the second perspective view;

FIG. 5 is a left view of the first perspective view;

FIG. 6 is a right view of the second perspective view;

FIG. 7 is a top view thereof; and,

FIG. 8 is a bottom view thereof.

The broken lines shown are included for the purpose of illustrating the unclaimed portions of the bottle and form no part of the claim.
